UNITED STATES PATENT OFFICE.

JOHN B. MARTENS, OF CLEVELAND, OHIO, ASSIGNOR TO MORRIS CRAMER.

DIE-STOCK.

1,210,188.

Specification of Letters Patent. Patented Dec. 26, 1916.

Application filed May 4, 1916. Serial No. 95,462.

To all whom it may concern:

Be it known that I, JOHN B. MARTENS, a citizen of the United States, residing at Cleveland, in the county of Cuyahoga and State of Ohio, have invented a certain new and useful Improvement in Die-Stocks, of which the following is a full, clear, and exact description, reference being had to the accompanying drawings.

10 The object of this invention is to provide a very simple, efficient and compact multiple die stock. My die stock is adapted for use of plumbers, gas fitters, steam fitters, etc. It provides means whereby with one tool a 15 number of sizes of pipes may be threaded, without requiring any change in the tool.

One of the characteristics of my die stock is a hollow frame having the dies on the interior, with the guiding bushings immediately adjacent on the outside. This enables 20 the threading of very short pipes, if desired. Access to the dies is provided by separation 25 of the frame. My die stock has a number of other specific advantages which will become apparent from the following description of a preferred embodiment of it.

In the drawings, Figure 1 is a side elevation of the die stock, the handles being partly indicated by broken lines; Fig. 2 is 30 an end view of the die stock; Fig. 3 is an elevation looking at the inner face of one of the two halves of the die stock; Fig. 4 is a central cross section.

My invention readily adapts itself for a 35 die stock carrying four sizes of dies, and such is the construction shown in the above drawings. When the number of dies carried is an even number, it is possible to make the stock in two parts, which are exact duplicates of each other, thus simplifying the construction and reducing the cost.

As shown in the drawings, the frame of the stock consists of two identical castings designated 10—10. Each casting comprises 45 mainly two substantially flat sides 11 and 12 at right angles to each other; two sleeves 13 and 14 on the outer face of the sides (located centrally and radially and secured by flaring portions 15); tubular ears 16 and 17 at the 50 free edges of the sides, and inwardly extending arms 18 and 19 at the ends of the side portions. When two castings having

characteristics above described are placed edge to edge, they provide a hollow four sided box-like frame. The ears 16 and 17 of one casting align with the corresponding ears of the other casting, and the end arms 18 and 19 of the two castings overlap each other. In this position the two castings are secured together by pintles occupying the 55 aligned ears at the edges of the castings. These pintles may readily be in the form of bolts 20 with thumb heads 21 and nuts 22 on the other ends. Where the two end arms overlap they have registering threaded holes 60 65 30 and 31 which are concentric of the axis of the stock. Into these holes the handles 35 are screwed.

I have thus provided very simply, a hollow four sided frame provided with handles 70 projecting from its ends and provided with four radially located sleeves. Each of the side portions is adapted to carry dies for 75 threading a pipe, while the sleeves are adapted to carry corresponding bushings for centering the pipe to be threaded. One of the bushings is indicated at 40. They are adapted to be held in the sleeves by thumb screws 41. These bushings are of the usual 80 form. They preferably have flanges overhanging the ends of the sleeves and have recesses for the reception of the thumb screw. The bushings vary only in interior diameter, according to the sizes of pipe to which the 85 dies correspond.

In the construction illustrated, there are four sets of dies, each set consisting of two die blocks 50 and 51 carried on the inner side of a side portion of the frame. Each of these side portions has base ribs 60 furnishing an accurate seat for the dies, and has also side ribs 62 and 63 forming guides for 90 the side edges of the dies. These side ribs, at the inner angle where the two side portions are rigidly connected together, are 95 preferably merged into one integral rib as shown at 63.

The dies are held on the base ribs and between the side ribs by screw bolts 70, which pass through the dies into the side portions. 100 The dies are accurately locked in position by set screws 71 threaded through the end arms 18 and 19 and bearing against the ends of the dies. The arms are reinforced at

these points by bosses 73 on the inner faces of the arms 18 and bosses 72 on the outer faces of the arms 19. These set screws take up any looseness around the bolts 70, and the 5 bolts and set screws together accurately hold the dies in position.

With such a construction as described it is very simple to turn a thread on a pipe of the desired size, the pipe being suitably held 10 and the bushing passed over it and the die stock turned to cause the die to cut the thread in the usual manner. By having the capacity in one tool for four sizes, the plumber has at his disposal means for turning 15 all of the threads usually encountered in his class of work; for instance, one tool may provide for threading pipes known as three-eighths, one-half, three-fourths and one inch, respectively. For other classes of 20 work other sizes of dies may be used.

To change the dies it is only necessary to take out one or both of the pintles 20, thus leaving the halves hinged together on the other pindle, or entirely disconnecting the 25 halves, if both bolts are removed. It should be noted that any looseness at the hinge pintles does not change the accuracy of the presentation of the bushing to the die, as each sleeve is rigidly connected with the 30 part of the structure which carries the corresponding pair of dies. However, there need be no material looseness between the two halves of the die stock for the handles screwing into the overlapped end arms 35 surely lock the two halves together.

By carrying the die on the inner side of the frame and the bushing directly outside thereof, a much shorter pipe may be threaded than where the pipe passes clear 40 through the stock on its diameter, as has been done heretofore. Moreover, the interior location of the dies protects them from accident. Should the die stock happen to be dropped, the form of the body and the 45 location of the handles is such that the set screw heads would be out of contact with the floor or surface on which the stock struck, and would thus be protected from any displacement. The interior location of 50 the dies not only protects them, but also makes it easier to keep them oiled.

One of the advantages of my die stock is its cheapness of construction. It uses standard dies, standard guide bushings, standard 55 screws and standard handles. The two parts of the frame being identical, a single pattern is required for casting. The machine work on the castings is simple and readily effected. The threading of the end arms is 60 preferably reserved until the ears are drilled and the two parts fastened together so that overlapped arms may be threaded at one operation. In use, the stock has the desired rigid frame, while by simply screwing out 65 the handles and taking out one of the hinge

bolts, access is allowed to the interior for changing the dies. By locating all the dies in the same radial central plane, the die stock is always central and balanced in use.

Having thus described my invention, what 70 I claim is:

1. In a multiple die stock, the combination of a plurality of separable frame members, dies carried by the frame members, said frame members having overlapping end portions, and handles for the die stock each closely engaging the corresponding overlapping end portions. 75

2. In a multiple die stock, the combination with a plurality of separable members 80 adapted to form a hollow frame, sets of dies carried by said members, each of said members having inwardly extending end portions, handles for the die stock, each threaded into the adjacent end portions and 85 thereby preventing relative movement of the parts.

3. In a multiple die stock, the combination of a hollow polygonal frame, dies carried thereby on the inner sides of the frame, and 90 means for holding radial bushings on the outer sides of the frame and respectively on the same side of the frame axis as the dies with which they coöperate.

4. In a die stock, the combination of a 95 hollow frame having a plurality of substantially flat sides, dies secured to the inner face of said sides, rigidly held radial sleeves on the outer side of the respective dies, and handles secured to the ends of the frame. 100

5. In a multiple die stock, the combination of a hollow frame having a plurality of interior faces, guide ribs along the edges of such faces, sets of dies between such ribs and clamped against the faces from the inner 105 side of the frame, and guide sleeves carried radially on the outer face of the same side of the frame opposite the center of said interior faces.

6. In a multiple die stock, the combination 110 of a hollow frame having a plurality of substantially flat faces, base ribs in each face, guide ribs along each face, a plurality of dies for each face, said dies being located between the guide ribs and resting against the 115 base ribs, clamping screws passing through such dies into the frame, set screws carried by the frame bearing against the ends of the dies, and means on the outer side of the frame for positioning a pipe centrally with 120 reference to the dies.

7. In a multiple die stock, the combination of relatively movable members, means for securing them together to make a hollow frame about an axis, and sets of dies and 125 guide sleeves rigidly carried by said members radially about said axis.

8. In a multiple die stock, the combination of frame members having ears at their edges, pins occupying said ears for holding the 130

members together to make a hollow box-like frame, and means on the members for carrying dies and bushings.

9. In a multiple die stock, the combination
5 of members carrying dies on their inner
sides and guide sleeves on their outer sides,
ears at the edges of said members, and pins
passing through said ears to hold them to-
gether to make a hollow frame.
- 10 10. In a multiple die stock, the combina-
tion of a hollow frame composed of mem-
bers provided with overlapping end por-
tions, handles extending through openings
in the overlapped parts, and means on the
15 members for carrying dies and bushings.

11. In a multiple die stock, the combina-
tion of a hollow box-like frame made up of
members having ears at their edges and pins
occupying said ears for holding the mem-
20 bers together, said members being provided
with overlapping inwardly extending arms,
handles extending through openings in the
overlapped arms, and means on the members
for carrying dies and bushings.

- 25 12. In a multiple die stock, the combina-
tion of a four sided frame made of two cast-
ings, each constituting two adjacent sides,
means for securing the castings together at
their edges, and means on the castings for
30 carrying dies and guide bushings.

13. In a multiple die stock, the combina-
tion of a four sided frame made of two cast-
ings, each constituting two adjacent sides,
means for securing the castings together at
35 their edges, means on the castings for car-
rying dies on the inner sides of the four
members, each of said four portions having
on its outer side a rigidly carried centrally
placed radial sleeve.

- 40 14. In a multiple die stock, the combina-
tion of a four sided frame made of two cast-
ings, each constituting two adjacent sides
and provided with hinge-ears at its edges,
pins occupying the hinge ears of both cast-
45 ings, and means on the castings for carry-
ing dies and guide bushings at each of the
four sides.

15. In a multiple die stock, the combina-
tion of two identical castings, each com-
50 prising a pair of side portions at right an-
gles to each other and transverse sleeves on
the outer sides of such portions and tubular
ears at edges of such portions, two of such
castings being adapted to be placed together
55 to make a square hollow frame with the ears
alining, pins occupying the alined ears, and
dies secured on the inner faces of the four
sides, and bushings occupying the sleeves.

16. In a multiple die stock, the combina-
60 tion of two identical castings, each com-
prising a pair of plate-like portions at right an-
gles to each other, and inwardly extending
end arms, two of such castings being adapt-
ed to be held together to make a square hol-
65 low frame with the end arms overlapping,

handles extending through openings in the
overlapped end arms, dies secured on the
inner face of the four sides, and bushings
occupying radial sleeves on the exterior of
the sides.

70

17. In a multiple die stock, the combina-
tion of a hollow frame comprising a plu-
rality of sides arranged about an axis, dies
carried on the inner faces of said sides, each
of said dies being opposite a die on the other
75 side of the axis, and guides carried by the
frame on the outer faces of the frame sides
in position to coöperate with the dies on the
same side of the frame axis.

18. In a multiple die stock, the combina-
tion of a hollow frame, a pair of handles
therefor extending in opposite directions
from the frame and located along the axis
thereof, dies on the inner sides of said
80 frame, and guides on the outer sides of the
frame, each guide being on the same side of
the frame axis as the die with which it co-
operates.

19. In a multiple die stock, the combina-
tion of a hollow box-like frame having a plu-
rality of faces arranged about an axis, dies
carried on the interior of said faces, set
screws carried by the frame for adjusting
the dies, and bushings carried by the frame
90 on the outer sides of the respective dies with
which the bushings coöperate.

20. In a multiple die stock, the combina-
tion of a hollow frame extending about an
axis, dies secured on the inner face of the
frame and arranged radially about the axis,
100 and guide sleeves on the outer sides of the
frame arranged radially about the axis, each
sleeve being on the same side of the axis as
the die with which it coacts.

21. In a multiple die stock, the combina-
tion of a hollow frame extending about an
axis, dies secured on the inner face of the
frame and arranged radially about the axis,
guide sleeves on the outer sides of the frame
110 arranged radially about the axis, each sleeve
being on the same side of the axis as the die
with which it coacts, end members for the
frame, and handles located at the axis and
engaging said end members.

22. In a multiple die stock, the combina-
tion of a hollow frame about an axis and
composed of a plurality of members remov-
ably secured together, whereby access may
be allowed to the interior, dies carried on
such interior, and guide sleeves coacting
120 with said dies located on the outer sides
thereof.

23. In a multiple die stock, the combina-
tion of a hollow box-like frame made of a
plurality of members separably connected
to extend about an axis, dies ar-
ranged radially about said axis and secured
to the inner faces of said members, guide
sleeves arranged radially about the axis and
secured on the outer faces of said members,
125 130

each guide sleeve coacting with the die on the same side of the axis of the frame.

24. In a multiple die stock, the combination of a hollow box-like frame made of a plurality of members separably connected together to extend about an axis, dies arranged radially about said axis and secured to the faces of said members, guide sleeves arranged radially about the axis and secured on the outer faces of said members, each guide sleeve coacting with the die on the same side of the axis of the frame, and removable handles secured to the frame substantially in line with the axis thereof.
- 10 25. In a multiple die stock, the combination of frame members, pins for securing said members together to make a hollow frame extending about an axis, dies on the interior of said frame, and guide sleeves 20 on the exterior of the frame.
- 15 26. In a multiple die stock, the combina-

tion of a hollow box-like frame composed of a plurality of members separably connected together, whereby access is allowed to the interior, bushings carried by the 25 frame on the exterior, overlapping end members for the frame, and handles occupying openings in the overlapped parts.

27. In a multiple die stock, the combination of a hollow frame extending about an 30 axis, dies on the interior of the frame, bushings on the exterior, each bushing coöperating with a die on the same side of the axis.

28. The combination of a hollow box-like frame providing a plurality of faces, dies 35 on the inner sides of said faces, and co-operating guide sleeves for the respective dies on the outer sides of the same faces.

In testimony whereof, I hereunto affix my signature.

JOHN B. MARTENS.
